Fig. 7

Fig. 8

FIG. 1 is a front elevational view of a viewer-magnifier to inspect skin prints to determine condition of the skin for cosmetic purposes;

FIG. 2 is a rear elevational view thereof;

FIG. 3 is a top plan view thereof;

FIG. 4 is a bottom plan view thereof;

FIG. 5 is a side elevational view thereof taken from the left side of FIG. 1;

FIG. 6 is a side elevational view thereof taken from the right side of FIG. 1;

FIG. 7 is a perspective view thereof taken from the front and slightly above; and

FIG. 8 is a perspective view thereof taken from the rear and slightly below.

I claim:

The ornamental design for a viewer-magnifier to inspect skin prints to determine condition of the skin for cosmetic purposes, substantially as shown and described.
